UNITED STATES PATENT OFFICE.

FRANK W. LANCASTER, OF JACKSONVILLE, FLORIDA.

COLLECTION DEVICE.

1,176,372.

Specification of Letters Patent. Patented Mar. 21, 1916.

Application filed November 17, 1915. Serial No. 62,068.

To all whom it may concern:

Be it known that I, FRANK W. LANCASTER, a citizen of the United States, residing at Jacksonville, in the county of Duval, 5 State of Florida, have invented certain new and useful Improvements in Collection Devices; and I do hereby declare the following to be a full, clear, and exact description of the invention, such as will enable others skilled in the art to which it appertains to make and use the same.

This invention relates to collection devices and particularly to devices of this character for use in churches.

15 The object of the invention is to provide a collection device designed to stimulate church contributions and embodying an improved construction for indicating those members of a church congregation who 20 have made their contribution and those members who have not.

A further object of the invention is to provide a collection device adapted to be opened through the manipulation of a plurality of locks the keys to which have been distributed to different persons so that the device can only be opened in the presence of all the persons holding keys.

With the above and other objects in view 30 the invention consists in the details of construction and in the arrangement and combination of parts to be hereinafter more fully described and particularly pointed out in the appended claim.

35 In describing the invention in detail reference will be had to the accompanying drawings wherein like characters of reference denote corresponding parts in the several views, and in which—

40 Figure 1 is a front elevation of a collection device constructed in accordance with the invention; Fig. 2, a rear view of the device with the door in open position; Fig. 3, a section on the line 3—3 of Fig. 1 on an enlarged scale, and Fig. 4, a section on the line 4—4 of Fig. 2.

45 Referring to the drawings the invention is shown as comprising a frame A including a top member 10, and side members 11 and 12. Suitably mounted in this frame is a plurality of members B, C and D.

The member B is disposed uppermost and includes a top wall 13, a front wall 14, and a bottom wall 15. The member B further 55 includes side walls 16 engaged against the side members 11 and 12 respectively of the

frame A. The top, bottom and front walls of the member B are connected by partitions 17 dividing the member B into compartments 18 in each of which is mounted a lock 19 adapted to be operated through the medium of a key inserted through a related key hole 20 in the front wall 14.

The member C is disposed beneath the member B and includes a front wall 21, a bottom wall 22 and side walls 23, the latter engaging against the side members 11 and 12 of the frame A. The bottom and front walls of the member C are connected by a plurality of vertical partitions 24 forming compartments 25. The front wall 21 of the member C extends upwardly into overlapping relation to the front wall 14 of the member B so as to form a slot 26 through which coins are adapted to be inserted in a manner that will hereinafter appear. Extending through the partitions 24 and into the side member 23 is a pivot rod 27 upon which is pivotally mounted an indicating lever 28 one of said levers being disposed in each compartment 25. The forward end of each lever 28 is provided with an indicating finger 29 adapted to travel in a related vertical slot 30 formed in the front wall 21. Rising from the bottom 22 and disposed in each compartment 25 is a guide rod 31 which is engaged in a recess 32 in the rear end of the indicating lever 28. This indicating lever 28 is provided with a central opening 33 through which the pivoted rod 27 passes. Secured to this pivot rod within the opening 33 of each lever 28 is one end of a coin slide-way 34 the other end of which bears against the inner side of the front wall 21 just beneath 35 a shoulder 35 formed on said front wall. Above each slot 30 there is indicated the name of the person who is to deposit a coin in the related compartment 25. This indication is of course on the outer side of the front wall 21. Also indicated on the outer side of the front wall 21 between the slots 30 are the words "Paid" and "Due", the word paid being disposed over the word due so that when the indicating finger 29 40 is in the upper end of the related slot 30 it will indicate that the collection has been paid by the person whose name appears above said slot, while on the other hand if the finger 29 is at the lower end of the slot 30 it will indicate that such person has not 45 paid what is due. It will be obvious that

when a coin is inserted through a slot 26 into the desired compartment it will move along the slide-way 34 and engage the rear end of the lever 28 and rock said lever to the dotted line position shown in Fig. 3 and thus move the finger 29 from the lower end of the slot 30 to the upper end of said slot. Under normal conditions the weight of the forward end of the lever 28 is such that the finger 29 will always be held in the lower end of the slot 30 by gravity.

The member D constitutes the lowermost member of the device while the member C 15 constitutes an intermediate member and it may be here stated that as many of these intermediate members may be employed as desired. The lower member D includes a front wall 35 and a bottom wall 36 together 20 with side walls 37 disposed against the side members 11 and 12 of the frame A. The front and bottom walls 35 and 36 are connected by a plurality of partitions 38 forming compartments 39 in each of which is 25 mounted a mechanism similar to the mechanism mounted in each of the compartments 25. The front wall 35 of the member D is disposed in overlapping relation to the lower portion of the front wall 21 to form 30 the requisite coin receiving slot 39. Formed on the bottom wall 36 are spaced lugs 40 connected by a pivot rod 41 and rotatable

on this rod 41 are lugs 42 formed integral with a door 43 which in closed position constitutes the rear wall of the device. This 35 door 43 carries a plurality of keepers 44 for receiving respective bolts 45 of the locks 19. By this construction it will be obvious that the door 43 can be released by operating the locks 19 and then swung to open 40 position to permit removal of the contents.

What is claimed is:—

A device of the class described comprising a casing having a plurality of compartments and a coin receiving slot communicating with each compartment and further having a vertical slot in its front wall communicating with each compartment, an indicating lever pivoted in each compartment, a finger on one end of said lever engaged in the slot, said lever being normally held by gravity in position to dispose the finger at the lower end of the slot to indicate non-payment, and said lever being operated by the weight of a coin inserted in the slot to a position to dispose the finger in the upper end of the slot to indicate payment.

In testimony whereof, I affix my signature, in the presence of two witnesses.

FRANK W. LANCASTER.
